UNITED STATES PATENT OFFICE.

HERBERT L. HUSSEY, OF WINTHROP, MASSACHUSETTS.

MAT FOR RUNNING-BOARDS.

1,130,292.

Specification of Letters Patent. Patented Mar. 2, 1915.

Application filed November 24, 1914. Serial No. 873,769.

To all whom it may concern:

Be it known that I, HERBERT L. HUSSEY, a citizen of the United States, and resident of Winthrop, in the county of Suffolk and State of Massachusetts, have invented certain new and useful Improvements in Mats for Running-Boards, &c., of which the following is a specification.

This invention relates to the mats detachably connected with running boards of motor vehicles and providing tread surfaces on which persons step on entering the vehicle.

The invention has for its object to provide improved means for detachably connecting a mat with a running board, the nature of said means being such that there is no interference with the top surface of the mat by the attaching means and no liability of detaching or displacing the attaching means when the mat is beaten to clean it.

The invention consists in the improvements which I will now proceed to describe and claim.

Of the accompanying drawings forming a part of this specification: Figure 1 represents a view of the under side of a mat embodying my invention; Fig. 2 represents a section on line 2—2 of Fig. 1, showing the mat secured to a running board; Fig. 3 is a perspective view of the mat-securing clip shown by Figs. 1 and 2, the clip being removed from the mat; Fig. 4 represents a view similar to Fig. 3, showing a modification.

The same reference characters indicate the same or similar parts in all the views.

In the drawings, 12 represents a mat which may be of any suitable material and construction and is preferably composed of fibrous material constituting a woven back and a top wiping surface made up of a multiplicity of fibers projecting outwardly from the back.

My invention does not relate to the construction of the mat, but to the means hereinafter described for securing the mat to the running board 13 of a motor vehicle or to any equivalent support on which it may be desirable to locate a mat.

In carrying out my invention I provide the mat with one or more, and preferably two, securing clips adapted to be inseparably engaged with the back portion of the

mat and to bear yieldingly on the under surface of the running board. 55

In the preferred embodiment of my invention shown by Figs. 1, 2 and 3, the clip is composed of a resilient U-shaped wire arm, including a neck portion 14, and spaced-apart branches 15 adapted to bear 60 simultaneously on the bottom of a running board. The clamping arm is provided with attaching means adapted to penetrate the back of the mat 12 and to bear on opposite edge portions of the mat in such manner 65 that the arm is inseparably connected with the mat and is not bodily displaceable in any direction, although the outer end of the arm is adapted to swing toward and from the bottom of the mat. Said attaching means, 70 in the embodiment of the invention now being described, include two bodkins 16 having pointed outer ends 17 and adapted to be thrust through the mat between the top and bottom surfaces thereof, said bodkins and 75 the clamping arm being preferably formed from a single piece of wire bent as clearly indicated by Fig. 3. The portions of the wire connecting the bodkins with the branches 15 of the clamping arm constitute 80 stop members adapted to bear at 18 on one edge of the mat to limit the insertion of the bodkins into the mat. The pointed outer ends of the bodkins are adapted to be bent or clenched against the opposite edge of the 85 mat and form stop members 19 (Fig. 2) preventing the withdrawal of the bodkins from the mat. It will now be seen that the bodkins are immovably and inseparably connected with the mat entirely below the wiping surface of the latter and that they hold 90 the clamping arm in such position that said arm is adapted to bear yieldingly on the under surface of the running board. When the described clip is detached from the mat 95 the clamping arm preferably springs inwardly toward the bodkins, as indicated by Fig. 3.

Fig. 4 shows a modification which embodies a single clamping arm 15^a and a single bodkin 16^a.

The bodkins are entirely below the upper surface of the mat, so that they cannot obstruct any part of said surface nor come in contact with feet stepping on the mat. 105 The clamping arms are so securely attached

to the mat that they are not liable to be displaced by the operation of beating or shaking the mat to clean it.

Having described my invention, I claim:

- 5 1. A mat provided with a securing clip composed of a resilient clamping arm provided with penetrative attaching means inserted in the body of the mat between the top and bottom surfaces of the latter, and 10 having stop members bearing on opposite edge portions of the mat, said clamping arm being yieldingly pressed toward the bottom surface of the mat, and adapted to yieldingly secure the mat to a running board.
- 15 2. A mat provided with a securing clip composed of a resilient U-shaped clamping arm composed of a neck and two spaced-apart branches adapted to bear simultaneously on the bottom of a running board, and 20 provided with bodkins inserted in the body of the mat between the top and bottom surfaces of the latter and having bent portions constituting stop members bearing on opposite edge portions of the mat, said clamping 25 arm being yieldingly pressed toward the bottom surface of the mat.
3. As an article of manufacture, a mat-

securing clip composed of a resilient clamping arm having integral penetrative attaching means insertible in the body of a mat between the top and bottom surfaces thereof and engageable with opposite edge portions of the latter, the clamping arm being pressed yieldingly toward the attaching means and adapted to bear yieldingly on the bottom of 30 a running board supporting a mat to which the arm is secured.

4. As an article of manufacture, a mat-securing clip composed of a U-shaped resilient clamping arm including a neck and 40 spaced-apart branches provided with penetrative bodkins insertible in the body of a mat and engageable with opposite edge portions of the latter, the clamping arm being pressed yieldingly toward said bodkins and 45 adapted to bear yieldingly on the bottom of a running board supporting a mat to which the arm is secured.

In testimony whereof I have affixed my signature, in presence of two witnesses.

HERBERT L. HUSSEY.
